UNITED STATES PATENT OFFICE.

CHARLES E. FULLER, OF OMAHA, NEBRASKA.

STRINGER-SUPPORT.

1,144,031.

Specification of Letters Patent. Patented June 22, 1915.

Application filed February 9, 1911. Serial No. 607,633.

To all whom it may concern:

Be it known that I, CHARLES E. FULLER, a citizen of the United States, residing at Omaha, in the county of Douglas and State 5 of Nebraska, have invented certain new and useful Improvements in Stringer-Supports, of which the following is a specification.

This invention relates to a stringer support or hanger, and particularly to a folding hanger which will be automatically retracted into a pocket when not in use, so as 10 to be entirely out of the way, but at the same time capable of instant use when needed.

It is frequently desirable in warehouses, 15 railway cars, the holds of ships, etc., to provide temporary floors to support goods, and by my invention I provide a hanger of simple form which may be mounted in pairs in various suitable positions in the walls of 20 such structures and may then be used to support stringers upon which the temporary floors are carried. Only such hangers as are actually in use protrude from the wall; the other hangers being retracted automatically 25 as above stated, into pockets mounted in the wall, and these pockets are so formed as to be properly supported by the framework of the structure, and so as to preclude the passage of any material through the wall by 30 way of the openings into which the pockets are set. I also give to the hanger a form combining simplicity with strength, and incidentally secure other advantages which will be apparent from the description of the 35 preferred embodiment of the device in connection with the accompanying drawings, in which:—

Figure 1 is a section through a portion 40 of a freight car or similar structure showing the hanger supported by the walls thereof; Fig. 2 is a vertical section through a hanger, showing it in the retracted position; Fig. 3 is a perspective view of the hanger pocket with its pin; and Fig. 4 is a perspective view of the hanger proper.

Referring to the drawings, 1 represents the outside sheathing of a car or the like; 2 the inner sheathing and 3 a framing member. The exact arrangement of these parts 45 may of course be varied, they being merely details of the structure to which the hanger is applied. A cup-shaped hanger pocket 4 is set into the space between the inner sheathing 2 and the outer sheathing 1, 55 through an opening formed in the inner sheathing and is supported on the framing

member 3 by bolts 5, which pass through lugs 6 formed integrally with the pocket. The pocket 4 is provided with a flange 7 which is wide enough to lap any opening 60 existing between the pocket 4 and the sheathing 2, thus preventing the passage of any material from within the car to the space between the inner and outer sheathing. The proportions of the cup and the flange, etc., 65 may be varied to accord with the space available.

The position and form of the lugs 6 are dependent upon the form of the framing member 3 as will be apparent. The form 70 shown is therefore illustrative and I contemplate modifications therein sufficient to adapt the pocket to attachment to any structure for which it is suited.

A pivot pin 8 passes in a horizontal direction through the walls of the pocket and these walls are thickened by bosses 9 to give a better support to the pin. The bosses 9 have extensions 10 which serve as limit stops for the hanger proper as will later appear. 80 The pin 8 is retained in the hanger pocket by means of a nut 11 or by any suitable equivalent.

The hanger proper 12, consists of a bottom plate 13, having side flanges 14 which 85 serve to retain a stringer upon the hanger and to hold it in an upright position. These side flanges also materially strengthen the hanger. The hanger is pivoted upon the pin 8 and is provided with a counterweight 90 15 to the rear of the pivot, which weight is sufficient to swing the hanger upward into the pocket to the position shown in Fig. 2. The counterweight 15 extends past the flanges 14 to form the lugs 16 which co-act 95 with the extension bosses 10 and limit the outward movement of the hanger. The inward movement of the hanger is limited by bosses 17 on the flanges 14 which abut against the rear walls of the pocket.

An inspection of the drawing will show that when the hanger is out in its supporting position the end of the stringer comes close to the pivot pin 8, and this pin 8 together with the co-acting lugs 16 and bosses 105 10 furnish adequate support to the hanger. The hanger may be moved to its supporting position by pushing the counterweight 15 inward or by drawing the upper end of the hanger outward by means of the 110 finger hole 18 provided for that purpose.

In the use of the device the proper hang-

ers are moved to supporting position and the stringer 19 is placed upon them, the weight of the stringer serving to hold the hangers in position. A series of stringers thus supported carry the floor or other structure, and when the stringers are finally removed the hangers automatically fold into their pockets leaving the walls of the car, warehouse or the like free of all 10 projections. The hangers are thus protected from injury to themselves; offer no obstructions to articles placed near them, and they have no detached parts.

As will be apparent from Fig. 2 the center 15 of gravity of the counterweight 15 even in the retracted position of the hanger is to the rear of the pivot pin 8, so that even in such retracted position the counterweight acts to so hold the hanger, thus preventing 20 the hangers from being thrown outward in case the car or other vehicle to which it is attached pitches or rocks.

The structure above described is found 25 peculiarly suited for use in stock cars, which at times carry horses or cattle whose height requires that the interior of the car be free of horizontal platforms or partitions between the floor and the roof, while at other 30 times swine, sheep, or smaller live-stock are carried, whose height permits of division of the car into two or more sections, one above another. If the hangers be not required, it is important that they be retracted within 35 their shells or casings, in order that they may not cause injury to the stock. The same is true in the case of box cars in which furniture and the like is carried. By reason 40 of the automatic withdrawal of the hangers, no neglect or carelessness on the part of the shipper or of the train crew, can occasion injury to the crew or to merchandise. There is hence a material advantage in the 45 structure above described, as compared with other hangers requiring manual return of the supporting-member to its inoperative position. It also contributes to the ease or facility of placing the stringers in position, for the reason that until manually drawn out to operative position, the supporting-

member lies entirely within the wall of the 50 containing structure, and a stringer or beam can have its end seated in the hanger at one end and swung directly upward to a point above the hanger which is to support 55 its opposite end, preliminarily to drawing out and positioning such second hanger, whereas if both hangers be positioned prior to mounting either end of the stringer or beam in its support, it is necessary to move the second end laterally to clear the second 60 hanger, and this in turn necessitates a looseness of fit and an allowance in length that permits undesirable play of the stringer or beam when in position.

Having thus described my invention, what 65 I claim is:—

1. The combination of a supporting pocket; bosses formed in said pocket; a hanger pivoted therein adapted in one position to support a stringer or the like and in another 70 to be contained within the pocket; a counterweight adapted to urge the hanger toward the second named position in all positions of the hanger; and lugs on the hanger adapted to coact with the bosses in 75 the pocket to sustain the hanger when drawn outward to supporting position.

2. The combination of a wall including a supporting frame and a sheathing; a cup shaped hanger pocket inserted through said 80 sheathing; means for supporting the hanger pocket on the frame; a flange on the hanger pocket, adapted to lap the space between the pocket and the sheathing; a hanger pivoted in the pocket and adapted in one position to support a stringer and in another 85 to be contained within the pocket; and a counterweight formed integrally with the hanger and adapted constantly to urge the same toward the second named position. 90

In testimony whereof I have signed my name to this specification in the presence of two subscribing witnesses.

CHARLES E. FULLER.
